FIG.20

FIG. 1 is a front view of the paddle.

FIG. 2 is a back view of the paddle.

FIG. 3 is a side view of the paddle, with the opposite side being substantially identical thereto.

FIG. 4 is a top view of the paddle.

FIG. 5 is a bottom view of the paddle.

FIG. 6 is a front view of the paddle wherein the grip has been modified by providing the vertical grooved pattern.

FIG. 7 is a back view of the modified paddle of FIG. 6.

FIG. 8 is a side view of the modified paddle of FIG. 6, with the opposite side being substantially identical thereto.

FIG. 9 is a top view of the modified paddle of FIG. 6.

FIG. 10 is a bottom view of the modified paddle of FIG. 6.

FIG. 11 is a front view of the paddle wherein the grip has been modified by providing a horizontal groove pattern.

FIG. 12 is a back view of the second modified paddle of FIG. 11.

FIG. 13 is a side view of the second modified paddle of FIG. 11, with the opposite side being substantially identical thereto.

FIG. 14 is a top view of the second modified paddle.

FIG. 15 is a bottom view of the second modified paddle.

FIG. 16 is a front view of the paddle wherein the grip has been modified by providing a circular dimple pattern.

FIG. 17 is a back view of the third modified paddle of FIG. 16.

FIG. 18 is a side view of the third modified paddle of FIG. 16, with the opposite side being substantially identical thereto.

FIG. 19 is a top view of the third modified paddle of FIG. 16.

FIG. 20 is a bottom view of the third modified paddle of FIG. 16.

We claim:

The ornamental design for a paddle, as shown and described.
